CABLE OR CONDUIT SUPPORT

Andrew S. Kinsinger, Gordonville, Pa., assignor
to Gilme Industries, Inc., a corporation of
Michigan

Application September 15, 1950, Serial No. 185,090

5 Claims. (Cl. 242—85)

1

One of the objects of my invention is to provide a structure for mounting a cable or flexible conduit supply reel on a trench digging attachment for tractors by which a flexible cable or conduit may be laid in the trench excavated as the attachment is advanced over the ground.

Another object of my invention is to provide a structure for mounting a reel for cable or conduit on a mobile unit in which the securing means for the reel are readily accessible from either side of the support for readily attaching, removing and replacing reels.

A further object of my invention is to provide an arrangement of rotatable member having differentially formed flanges on opposite ends thereof where the smaller flange serves as an annular bearing surface, while the larger flange serves as a connecting means for detachably mounting a reel for cable or conduit.

Still another object of my invention is to provide a construction of cable or flexible conduit guide for directing a cable or flexible conduit into an open trench excavated by a digger attachable to a tractor.

Other and further objects of my invention reside in the trench digging and cable or flexible conduit laying attachment for tractors as set forth more fully in the specification hereinafter following by reference to the accompanying drawings in which:

Figure 1 is a side elevational view of the composite excavating and flexible cable or conduit laying attachment for tractors showing the arrangement of my invention; Fig. 2 is a transverse sectional view taken substantially on line 2—2 of Fig. 1, the view being shown on an enlarged scale; Fig. 3 is a transverse sectional view taken substantially on line 3—3 of Fig. 1, the view being shown on an enlarged scale; Fig. 4 is a vertical sectional view on an enlarged scale taken substantially on line 4—4 of Fig. 1; Fig. 5 is a view similar to the view shown in Fig. 4 but illustrating the component parts of the reel assembly in juxtaposition; Fig. 6 is a plan view showing a fragmentary portion of the top of the attachment of my invention and illustrating the table on which the reel carrying the flexible cable or conduit may be mounted; Fig. 7 is a horizontal sectional view taken substantially on line 7—7 of Fig. 1 and showing the reel which carries the flexible cable or conduit in position; Fig. 8 is a transverse sectional view taken substantially on line 8—8 of Fig. 1 and showing more particularly the manner in which the tubular guide for the flexible cable or conduit may be detached and attached with respect to the rear of the digging

2

tool; Fig. 9 is a fragmentary longitudinal sectional view taken substantially on line 9—9 of Fig. 1; and Fig. 10 is a fragmentary vertical sectional view taken substantially on line 10—10 of Fig. 1.

My invention is directed to a composite construction of trench excavating and cable or flexible conduit laying attachment for tractors. The excavating portion of the attachment of my invention is similar to the structure disclosed in my co-pending application Serial Number 149,379 for Composite Excavating and Pipe Laying Machine. The attachment of my present invention includes a shaped tubular guide which is mounted on the depending excavating tool and which extends from a position adjacent the rear of the excavating tool to a position above the frame of the attachment and in line with a supply reel. The supply reel is rotatably mounted upon a spindle carried by the top of the frame of the attachment and is adapted to revolve for unwinding flexible cable or conduit which is directed through the tubular guide and laid in the open trench excavated by the excavating tool as the tractor which carries the attachment advances along the ground. The excavating tool operates under ground and the flexible cable or conduit follows along behind the tool unwinding from the reel. Thus a rapid cable or conduit laying operation is accomplished as the trench is dug resulting in great saving in labor and installation cost.

Referring to the drawings in detail, reference character 1 designates a frame structure terminating in lugs represented at 2 and 3 which are attachable to the hydraulic lift of a tractor. The frame structure is symmetrically constructed so that there are four such lugs represented by lugs 2 and 3 distributed quadrilaterally of the frame structure for attachment to similarly located arms on the hydraulic lift. The frame structure 1 supports a centrally disposed I beam 4 to the opposite sides of which the ends of the frame structure 1 are secured as represented at 1a, 1b, 1c and 1d. The lower flange 4a of the I beam is slotted as represented at 4a' and 4a'' for the passage of downwardly extending plates 5 and 6 which form the support for the excavating tool shown at 7. The I beam 4 is reinforced at the junction of the plates 5 and 6 with the I beam 4 by means of plates 8 and 9 extending intermediate the flanges 4a and 4b of the I beam and substantially in alignment with the terminating ends of the members 1a, 1b, 1c and 1d constituting the frame structure 1. The transversely extending bolt member 10 secures the plates 5

and 6 to the I beam 4. The plate members 5 and 6 are reinforced with respect to I beam 4 by a rearwardly disposed abutment block 11 extending transversely of flange 4a of I beam 4 immediately behind depending plates 5 and 6. The front of the plates 5 and 6 are reinforced with respect to the flange 4a of I beam 4 by angularly inclined brace bar 12 having a yoke 14 at its lower end embracing plates 5 and 6 and secured thereto by transverse bolt 15 and having a yoke 16 adjacent its upper end which embraces the lower end of a strap 17 welded at 17a to the underside of flange 4a of I beam 4. Transverse bolt 18 extends through the ends of yoke 16 and through the open loop of strap 17 embraced thereby for fastening brace bar 12 to I beam 4 and thus serving as a restraining link for the excavating tool which is subjected to very severe strains during the digging operation.

The front of the excavating tool carries a reinforcement bar 19 which abuts with the cutting head of the tool represented at 20 and disposed at an angle to the depending plates 5 and 6. The cutting tool 20 is mounted upon the front of block 21 into which the terminating ends of plates 5 and 6 extend. The rearward extension of block 21 is provided with a vertically extending socket 22 therein into which the end of a detachable bar member 23 may be inserted. The detachable bar member 23 extends linearly along the rear of plates 5 and 6 and provides a detachable mounting means for the tubular guide 24 which is welded to the detachable bar member 23 as represented at 24a. Fig. 8 shows more clearly the attachment bracket 25 carried by the rear of plates 5 and 6 and through which the detachable bolt 26 is attached to be fastened in detachably securing bar 23 to the rear of the excavating tool.

The tubular guide 24 is substantially S shaped in contour having a lower curved portion 24b terminating rearwardly of the excavating tool 20 and substantially in the center line of the block 21 through which the flexible cable or flexible conduit 27 is delivered and laid in the excavated trench 28 as the excavating tool 20 advances through the earth at 29. The upper end of the tubular guide 24 is curved as represented at 24c and extends around the end 4c of the I beam 4 and terminates adjacent the supply reel 30.

In order to mount the flange 30a of supply reel 30 on the attachment of my invention I secure a tubular socket 31 to the top of the flange 4b of I beam 4 in a position over the digging tool 20 substantially midway of the distance of the fastening for the depending plates 5 and 6 on I beam 4 and the terminus of the digging tool 20. The socket 31 is welded to the top flange 4b in a position in which a condition of balance and equilibrium may be maintained throughout the laying of the flexible cable or conduit carried by reel 30. The socket 31 provides a mounting means for stub shaft 32 which extends in a vertical direction and is keyed to socket 31 by means of a pin 33 extending through a diametrically aligned aperture 31a in socket 31 and through a diametrical aperture 32a in stub shaft 32.

The stub shaft 32 forms a spindle over which the rotatable member 34 is placed. Rotatable member 34 has a spacing collar 34a thereon which extends around stub shaft 32. The flange of rotatable member 34 carries screw threaded studs shown at 35, 36, 37 and 38 with coating lock nuts thereon indicated at 35a, 36a, 37a and 38a for maintaining the screw threaded studs in a fixed position in engagement with the screw

threaded apertures 39, 40, 41 and 42 carried by the rotatable member 34. The lower flange 30a of the reel 30 may be formed with reinforcing interiorly screw threaded sleeves shown more clearly in Figs. 4 and 5 at 40a and 42a for receiving the ends of the coating screw threaded studs for maintaining the reel 30 in rigid assembly with rotatable member 34. Member 34 is thus arranged to revolve with the reel 30 around stub shaft 32 as a spindle as the flexible cable or conduit 27 unwinds from the reel 30 as the digging tool is pulled along the ground by a tractor. The rotatable member 34 attached to the reel 30 insures operation of reel 30 uniformly about the axis of stub shaft 32 throughout the various conditions of loading that is at the commencement of the laying operation when the reel is entirely loaded as well as at the end of the laying operation when the reel 30 is substantially empty. The rotatable member 34 has differentially formed flanges 34b and 34c interconnected by the spacing collar 34a. The smaller flange 34b serves as the bearing means for the rotatable member 34, while the larger flange 34c serves as the mounting means for the reel 30.

Extended lengths of flexible cable and conduit may be laid using the structure of my invention as it is extremely simple to replace an empty reel 30 with a loaded reel and stop the machine long enough to splice the ends of the cable or conduit. The entire assembly embodying the cable and conduit laying mechanism is readily detached and attached to the machine by removal of the stub shaft 32 and the reel 30 and associated rotatable member 34 and by withdrawal of bolt 26 and removal of bar 23 for detaching the tubular guide 24.

I have found the cable and flexible conduit installation attachment for the excavator of my invention highly practical in its construction and operation for the rapid laying of extended lengths of cable or flexible conduit and while I have described my invention in certain of its preferred embodiments, I realize that modifications may be made and I desire that it be understood that no limitations upon my invention are intended other than may be imposed by the scope of the appended claims.

What I claim as new and desire to secure by Letters Patent of the United States is as follows:

1. In a cable or flexible conduit laying machine, a frame, a vertically disposed socket support carried by said frame, a vertically extending stub shaft mounted in said socket support and extending in a substantially vertical direction from said frame, a rotatable member positioned on said stub shaft and having flanges of two different sizes at opposite ends thereof, the smaller flange rotatably engaging said socket support, a substantially horizontally disposed rotatable detachable reel carrying cable or flexible conduit mounted on the larger flange of said member and a tubular guide detachably mounted on said frame and extending from a position adjacent said reel to a position terminating behind the frame for directing cable or flexible conduit from the reel to the rear of the frame.

2. In a cable or flexible conduit laying machine as set forth in claim 1 in which said vertically disposed socket support terminates to a flat annular bearing surface and wherein the smaller of the flanges on said rotatable member has an annular bearing face rotatably engaging said aforementioned flat annular bearing surface and

wherein the larger of the flanges of said rotatable member carries locking means for establishing locking connection with the rotatable detachable reel mounted thereon.

3. In a cable or flexible conduit laying machine as set forth in claim 1 in which the larger of the flanges of said rotatable member carries vertically adjustable locking screws therein engageable with the rotatable detachable reel and means for adjusting said locking screws in said rotatable detachable reel from a position beneath said rotatable member in positions accessible from opposite sides of said socket support.

4. In a cable or flexible conduit laying machine as set forth in claim 1 in which said vertically disposed socket support terminates in a flat annular bearing surface and wherein said rotatable member has a spacing collar disposed between said flanges and wherein said smaller flange terminates in an annular bearing face rotatably engaging said aforementioned flat annular bearing surface and wherein the larger flange of said rotatable member carries screws that are vertically adjustable therein to engage said rotat-

able detachable reel from a position on opposite sides of said socket support.

5. In a cable or flexible conduit laying machine as set forth in claim 1 in which said rotatable detachable reel includes sleeve members embedded at spaced intervals on vertical axes flanges which are interiorly screw-threaded for receiving locking screws carried by the larger flange of said rotatable member, said locking screws engaging the interior screw-threads in said sleeve members, and means for maintaining said locking screws in engaged positions in said sleeve members.
